(57) **CLAIM**

The ornamental design for a magnetic mini-basket, as shown and described.

DESCRIPTION

FIG. 1 is a top plan view of a magnetic mini-basket;

FIG. 2 is a front elevational view thereof;

FIG. 3 is a bottom view thereof;

FIG. 4 is a left elevational view thereof, the right elevational view being a mirror image thereof;

FIG. 5 is a rear elevational view thereof; and,

FIG. 6 is an isometric view thereof, adhered to a surface.
